UNITED STATES PATENT OFFICE.

ARTHUR B. MODINE, OF RACINE, WISCONSIN.

DESIGN FOR A CABINET.

Application filed November 19, 1926. Serial No. 19,782. Term of patent 14 years.

To all whom it may concern:

Be it known that I, ARTHUR B. MODINE, a citizen of the United States, residing at Racine, in the county of Racine and State of Wisconsin, have invented a new, original, and ornamental Design for a Cabinet, of which the following is a specification, reference being had to the accompanying drawing, forming a part thereof.

The figure is a perspective view of a cabinet, showing my new design.

I claim:

The ornamental design for a cabinet as shown.

ARTHUR B. MODINE.
